UNITED STATES PATENT OFFICE

169,107

CALENDAR SHEET

Whitney W. Potter, St. Joseph, Mo.

Application March 30, 1950, Serial No. 8,880

Term of patent 14 years

(CL. D59—2)

To all whom it may concern:

Be it known that I, Whitney W. Potter, a citizen of the United States, residing at St. Joseph, in the county of Buchanan and State of Missouri, have invented a new, original, and ornamental Design for a Calendar Sheet, of which the following is a specification, reference being had to the accompanying drawing, forming part thereof.

The figure is a front elevation of a calendar sheet, embodying my new design.

The calendar sheet is of conventional thickness, and the dominant features of my design reside in those portions shown in full lines, the design being characterized by large rectangular areas associated with small rectangular areas, said larger areas having short lines extending

from the top center and lower corners thereof toward the middle, all as shown.

I claim:

The ornamental design for a calendar sheet, as shown and described.

WHITNEY W. POTTER.
